Primary Examiner — Calvin E Vansant*Assistant Examiner* — Mark T. Philipp(74) *Attorney, Agent, or Firm* — Aird & McBurney LP(57) **CLAIM**

We claim the ornamental design for a payout apparatus, as shown and described.

DESCRIPTION

FIG. 1 is an isometric view of a payout apparatus showing the new design;

FIG. 2 is a front view thereof;

FIG. 3 is a rear view thereof;

FIG. 4 is a left side view thereof;

FIG. 5 is a right side view thereof;

FIG. 6 is a bottom view thereof; and,

FIG. 7 is a top view thereof.

The broken lines in the drawings depict portions of the payout apparatus that form no part of the claimed design.

1 Claim, 7 Drawing Sheets(56)
